UNITED STATES PATENT OFFICE.

CHARLES E. H. ARMBRUSTER, OF DENVER, COLORADO.

SYSTEM FOR THE TREATMENT OF DISEASES OF THE HUMAN BODY BY VACUUM OR AIR-PRESSURE.

1,172,660.

Specification of Letters Patent.

Patented Feb. 22, 1916.

Application filed September 2, 1914. Serial No. 859,908.

To all whom it may concern:

Be it known that I, CHARLES E. H. ARMBRUSTER, a citizen of the United States, residing at Denver, in the county of Denver and State of Colorado, have invented certain new and useful Improvements in Systems for the Treatment of Diseases of the Human Body by Vacuum or Air-Pressure, of which the following is a specification.

10 My invention relates to apparatus for the therapeutic treatment of diseases, by vacuum and air-pressure, and its object resides in the provision of a system of coöperative devices by the use of which different parts 15 of the human body may be relieved from air pressure, subjected to air pressure exceeding atmospheric, or alternately relieved from pressure and subjected to air of atmospheric or higher pressure.

20 When applied to the thorax of the body, the system may be effectively employed for the treatment of tuberculosis of the lungs, pneumonia and other pulmonary diseases, by producing artificial respiration, and it 25 includes means which may be used while the above treatment is carried on, to aid the circulation of blood of the patient, and to thereby relieve the heart, and heal diseased tissues by forcibly driving the blood into 30 the lungs.

The apparatus comprised in the system may also be used to artificially produce hyperemia for the purpose of treating any part of the body which is wasted or is otherwise diseased by mal-nutrition or other causes, and it furthermore includes means whereby it may be applied to the head for the purpose of forcing air directly into the lungs and producing artificial respiration in 40 case of asphyxiation.

With the above objects in view, I provide a casing which is constructed to be applied to the body so as to form an air-tight chamber over or around a part thereof, and a 45 means capable of exhausting air from said chamber or supplying compressed air to the same, such as a combined pressure and exhaust pump.

The flow of air between the chamber and 50 the inlet and outlet openings of the pump, is controlled by an appliance which includes a mechanically operating valve capable of

alternating the flow of air to and from the chamber by directing its passage through a plurality of ports in a housing in which it 55 has its movement.

Manually adjustable valves for closing or opening the ports above referred to, permit of regulating the supply or exhaust of air to and from the chamber at the will of the 60 operator, it being possible within the range of the appliance, first, to alternately exhaust the air from the chamber and connect it with the atmosphere; second, to alternately exhaust the air from the chamber 65 and introduce air of more than atmospheric pressure thereinto; third, to alternately drive air under compression into the chamber and connect the same with the atmosphere; fourth, to continuously maintain a 70 supply of compressed air within the chamber; fifth, to continuously maintain a partial vacuum within the chamber, and sixth, to continuously place the chamber in communication with the atmosphere. 75

The controlling appliance also includes means whereby the degree to which air is exhausted from the chamber, or air under compression is supplied thereto by the action of the pump, may be varied at will, and it furthermore provides an adjustment whereby the proportional lengths of the alternate periods of varying air pressures in the chamber may be changed within determinate limits. 85

An embodiment of my invention has been shown in the accompanying drawings in the various views of which like parts are similarly designated, and in which,

Figure 1 represents a view of the different elements comprised in my system, together with the means whereby they are coöperatively connected, Fig. 2, a section along the line 2—2, Fig. 1; Fig. 3, a section along the line 3—3, Fig. 1; Fig. 4, a section 95 along the line 4—4, Fig. 1; Fig. 5, an elevation of the element of my system which in its operation is applied to the human body, in a form adapted to incase the head, and Fig. 6, an elevation of the same element in 100 a form in which it may be applied to one of the limbs of the body.

The casing which in the operation of the system is applied to the body for producing

an air-tight chamber over or around a part thereof, and the controlling appliance by which the flow of air to and from the casing is regulated, have been made subjects 5 of separate applications for patent, filed synchronously with the present application, and their constructions will for this reason be but briefly referred to in the following description.

10 Referring to the drawings by numerical reference characters, the numeral 2 designates a combined pressure and exhaust pump, and 3 an electric motor which has a driving connection therewith. The pump 15 which may be of any desired construction, has been shown in the drawings in the form of a rotary blower having an air inlet 4 and an air outlet 5.

The casing which in practice is applied 20 to the body of the patient for the production of an air-tight chamber over or around a diseased part thereof, has been designated in the drawings by the numeral 6.

The casing shown in Fig. 1 is designed 25 particularly to be placed around the thorax of a patient for the treatment of pulmonary diseases, and it has been illustrated in connection with a garment 7 made of soft rubber or other flexible and elastic material, 30 formed to incase the abdomen and lower limbs of the body, for the purpose of promoting the circulation of blood while the apparatus is in operation. I desire it understood, however, that the garment does 35 not form an essential part of this element of my system and that the casing may be used separately by merely detaching the garment and closing the end at which it was connected thereto, around the corresponding 40 part of the body.

The casing consists briefly, of two halves which are connected by suitable clamping means and which are composed of material sufficiently rigid to withstand the air pressure either within or without the casing.

45 The casing has openings as at 8, 9 and 10, to respectively receive the neck, the arms, and the part of the body below the thorax, and surrounding these openings it has means 50 which are adjustable to engage the surface of the parts extending therethrough, so as to provide air-tight junctures which completely separate the chamber formed between the wall of the casing and the part 55 of the body within the same, from the surrounding atmosphere.

The third element of my system comprises a controlling appliance including an oscillating valve 12 which is operated by 60 means of an electric motor 13 through the instrumentality of a transmission mechanism which in the construction shown, includes a pair of friction disks 14 and 15 and an adjustable wheel 16 which friction- 65 ally engages the faces thereof. The disk

14 is operatively connected with the motor by means of a worm connection 17, and the shaft of the other disk, 15, carries a crank 18 provided at its end with a roller which during rotation of the said shaft alternately 70 engages two cam faces 19 and 20 on a bar 21. The bar is at one of its ends mounted for reciprocation on a rocker arm 22 and its opposite end is pivoted on the wrist of a crank 23 which connects with the before- 75 mentioned valve 12 exteriorly of its housing 24. The cam face 19 is formed on a block 27 which is slidably mounted on the bar to which it may be secured in one of two determinate positions by means of a set 80 screw 26, and the other cam face is formed on a block 25 which is similarly mounted on an arm 28 which is pivoted to the bar as at 29. A set screw 30 on the arm 28 projects through a slotted segment 31 extending in opposite directions from the bar, and serves to secure the arm either in its normal 85 position in alinement with the bar, or in angular relation to the same at either end of the segment as indicated in broken lines in 90 Fig. 2.

The valve housing 24 comprises a central chamber 32 in which the oscillating valve 12 is mounted, and three smaller chambers 33, 34 and 35 which connect with the first- 95 mentioned chamber by means of ports 36 and with the atmosphere by means of ports 37. The primary chamber 32 has in the lower portion of its wall a port 38 for its connection with the atmosphere. Rotatably 100 fitted within the secondary chambers are cylindrical valves 39 provided with handles 40 which project through the respective ports 37, for their adjustment. The valves in the chambers 34 and 35 are adapted to 105 either open or close the air passages 36 and at the same time close or open the respective atmosphere-ports 37, when placed in the positions determined by the engagement of their respective handles with the side 110 edges of the ports through which they extend, and the valve in the chamber 33 is formed to either open or close the port which connects the chamber with the atmosphere, while leaving the passage between 115 the same and the primary chamber, continually open. The valve chamber 33 is connected with the body-casing 6 by a conduit 41, the chamber 35 connects with the inlet opening 4 of the pump through the medium 120 of a pipe 42, and a conduit 43 which includes an oil separator 44 of suitable construction, is provided to connect the air outlet 5 of the pump with the third chamber 34.

Having thus briefly described the construction of the elements comprised in the system and the method by which they are cooperatively connected, I will now proceed to explain the operation of my invention 125 and the manner in which the controlling ap- 130

pliance may be employed to produce the different effects hereinabove enumerated.

After the casing has been applied to the body in the manner hereinbefore described, 5 the electric circuit in which the two motors are connected, is closed for their actuation, and the valves which control the flow of air between the pump and the casing, and the primary valve chamber are adjusted in accordance with the effect it is desired to produce. It will be observed that the oscillating valve 12 places the continuously open passage 36 of the chamber 33 which connects with the body casing, alternately in connection with the two chambers 34 and 35 which respectively connect with the outlet opening and the inlet opening of the pump. Now, when it is desired to alternately exhaust the air from the casing 6 and place 20 the same in communication with the atmosphere, the valves are placed in the position shown in the drawings in which the atmosphere ports 37 of the chambers 33 and 35 which respectively connect with the casing 6 and with the inlet of the pump, are closed while the corresponding port of the chamber 34 which is connected with the air outlet of the pump, is opened and the passage 36 between the last mentioned chamber and the 25 chamber 32 is closed. When the valve is moved to the position shown in full lines in Fig. 3, the air contained in the casing 6 will be drawn through the pipe 41 into the chamber 33 and through the therewith communicating chamber 35 into the conduit 42 through which it flows to the pump, and the compressed air which at the same time is delivered from the pump through its outlet opening 5 is simultaneously discharged 30 through the port 37 of the chamber 34 with which said opening connects. When the oscillating valve 12 moves to its other position which is indicated in Fig. 3 of the drawings in broken lines, the communication 35 between the two chambers 33 and 35 is discontinued and air of atmospheric pressure which had entered the valve chamber through the port 38 is admitted to the casing 6 through the continually open port 36 of the chamber 33. It follows that the part 40 of the body within the casing is subjected alternately to a partial vacuum and to atmospheric pressure, which compels the lungs of a patient to which the casing is applied to act for the inhalation and expulsion of air, and thereby open the air cells closed by disease, dry out the cavities and pus chambers, aid the expulsion of dead matter, and generally strengthen, feed and 45 heal the diseased tissues. If in connection with the casing 6 the rubber garment 7 is used, the opening of the casing around the part of the body below the thorax is left open, but the garment is closed around the 50 feet of the patient. When with the mem bers in this condition air is exhausted from the chamber in the casing and the therewith communicating garment, the external air pressure will cause the latter to collapse and tightly hug the parts of the body around 55 which it is applied, with the result that the blood in the said parts is driven to the upper portion of the body and into the lungs to stimulate the heart action and feed and heal the diseased tissues. If it is desired to subject the part of the body within the casing alternately to atmospheric pressure and air pressure exceeding atmospheric, the positions of the valves in the chambers 34 and 35 are reversed with the 60 result that by the oscillating movement of the valve 12 the chamber 33 is placed alternately in communication with the atmosphere and with the outlet opening of the pump instead of with the inlet opening as 65 above. Should it be required to continuously maintain a partial vacuum in the casing, the motor 13 is stopped, the valve 12 placed in the position shown in full lines in Fig. 3, and the valves in the chambers 34 and 35 placed in the positions in which they have been shown in the same figure. To maintain a continuous air pressure more than atmospheric, in the casing, the valve 12 is moved to the position shown in broken 70 lines and the position of the valves in the chambers 35 and 34 are reversed, and to connect the casing continuously with the atmosphere, it is but necessary to open the port 37 of the chamber 33 by adjustment of 75 the corresponding valve. 80

The degree of vacuum produced in the casing 6 during the operation of the system may be varied by partially opening the port 37 of the chamber 33, whereby to admit air into the casing, and the degree of air pressure within the casing may be regulated in a similar manner by permitting the escape of air from the same.

To vary the proportional lengths of the alternate periods of different air pressures within the casing, the block 25 of which the cam face 20 is formed, is moved to either end of the segment on the bar by adjustment of the arm 28 with the result that the 110 arc in the circle of movement of the roller at the end of the crank 18 between the ends of the faces 19 and 20, which normally are equal, are differently proportioned, and the valve 12 will remain longer in one of its 115 positions than in the other.

If it is desired to effect the different changes in the flow of air to and from the casing by means other than the valves in the chambers 34 and 35, the ports 37 of the 120 latter may both be closed and one or the other of the blocks 25 and 27 moved to a position farther away from the center of the circle in which the roller has its motion, whereby to reduce the extent of the move- 125 130

ment of the oscillating valve 12 and thereby place either one of the chambers 34 and 35 alternately in communication with the chamber 33 and with the atmosphere through the port 38.

In Fig. 5 of the drawings has been shown a form of the body casing which adapts it to incase the head of a patient. The casing which like the one hereinbefore described is composed of complementary halves, is tightly closed around the neck, and it has a glass-covered opening through which the face of the patient may be observed. By alternately exhausting air from a casing thus applied and admitting air of atmospheric or higher pressure into the same, respiration is artificially produced by alternately forcing air directly into the lungs and exhausting all or part of the same, a treatment which is especially beneficial in case of asphyxiation.

The form of the casing illustrated in Fig. 6, is designed to be placed around a part of the arm or leg of the patient for the purpose of artificially producing hyperemia to feed the tissues of the part within the casing with extra quantities of blood in case of mal-nutrition or anemia.

It will be understood that instead of using the rubber garment 7 in connection with the air-tight casing 6, another similar casing as for example that shown in Fig. 6, may be applied to another part of the body and air of more than atmospheric pressure introduced thereto at the same time that air is exhausted from the first-mentioned casing. Two or more of the casings may in this manner be used for other purposes as well and their connection with the pump can be regulated either by one controlling appliance or by separate appliances.

Having thus described my invention what I claim and desire to secure by Letters-Patent is:

1. In a system of the character described, a device capable of being applied to the human body for producing an air-tight chamber over or around a part thereof, a suction-producing element, and an appliance which automatically places the said chamber alternately in communication with the said element and with the atmosphere, and which includes means for its adjustment to place the chamber continuously in communication with either the atmosphere or the said element.

2. In a system of the character described, a device capable of being applied to the human body for producing an air-tight chamber over or around a part thereof, a source of fluid-pressure, and an appliance which automatically places the said chamber alternately in communication with the said source and with the atmosphere, and which includes means for its adjustment to

place the chamber continuously in communication with either the atmosphere or the said source.

3. In a system of the character described, a device capable of being applied to the human body for producing an air-tight chamber over or around a part thereof, a fluid-exhaust and compression element having fluid admission and delivery ports in connection with said chamber, and an appliance in said connection which automatically places the said chamber alternately in communication with the said admission-port and the said delivery port and which includes means for its adjustment to place the chamber continuously in communication with either port.

4. In a system of the character described, a device capable of being applied to the human body for producing an air-tight chamber over or around a part thereof, a fluid-exhaust and compression element having fluid admission and delivery ports in connection with said chamber, and an appliance in said connections which automatically places the said chamber alternately in communication with the said admission-port and the said delivery port and which includes means for its adjustment to vary the partial vacuum or the pressure produced in the chamber by its connection with the said element, to a selected degree, or to place the chamber continuously in communication with either port.

5. In a system of the character described, a device capable of being applied to the human body for producing an air-tight chamber over or around a part thereof, a fluid exhaust and compression element having fluid-admission and delivery ports in connection with said chamber, and an appliance in said connections, which is adjustable to place the chamber in continuous communication with either port.

6. In a system of the character described, a device capable of being applied to the human body for producing an air-tight chamber over or around a part thereof, a fluid exhaust and compression element having fluid admission and delivery ports in connection with said chamber and an appliance which automatically controls the connections of said chamber with the said ports and with the atmosphere and which includes means for its adjustment to place the chamber alternately in communication with either port and with the atmosphere, or to place the same continuously in communication with either port or with the atmosphere.

7. In a system of the character described, a device capable of being applied to the human body for producing an air-tight chamber over or around a part thereof, a fluid-exhaust and compression element hav-

ing fluid-admission and delivery ports in connection with said chamber, and an appliance, which automatically controls the connections of said chamber with the said 5 ports and with the atmosphere and which includes means for its adjustment to place the chamber alternately in communication with either port and with the atmosphere, to place the same alternately in communication 10 with the admission port and the delivery port, or to place the same continuously in communication with either port or with the atmosphere.

8. In a system of the character described, 15 a device capable of being applied to the human body for producing an air-tight chamber over or around a part thereof, a fluid-exhaust and compression element having fluid admission and delivery ports 20 in connection with said chamber, and an ap-

pliance which automatically controls the connections of said chamber with the said ports and with the atmosphere and which includes means for its adjustment to place the chamber alternately in communication 25 with either port and with the atmosphere to place the same alternately in communication with the admission-port and the delivery port, to place the same continuously in communication with either port or with 30 the atmosphere, and to vary the partial vacuum or the pressure produced in the chamber by its connection with the element, to a selected degree.

In testimony whereof I have affixed my 35 signature in presence of two witnesses.

CHARLES E. H. ARMBRUSTER.
